UNITED STATES PATENT OFFICE.

SOREN ROBERTSON SKOV, OF CLEVELAND, OHIO.

MILK-CAN.

No. 830,182.

Specification of Letters Patent.

Patented Sept. 4, 1906.

Application filed August 9, 1905. Serial No. 273,370.

To all whom it may concern:

Be it known that I, SOREN ROBERTSON SKOV, a citizen of the United States, residing at Cleveland, in the county of Cuyahoga and State of Ohio, have invented certain new and useful Improvements in Milk-Cans; and I do declare that the following is a full, clear, and exact description of the invention; which will enable others skilled in the art to which it applies to make and use the same.

My invention relates to improvements in milk-cans; and the invention consists in a milk-can provided with a separate and removable top portion.

As milk-cans are ordinarily made they are made with closed ends, except that the top has a comparatively narrow neck in its center and top through which the can is filled and emptied and through which also the can has to be internally cleaned. Now it is well-known that milk-cans as such, require the most diligent care at the best to keep them sweet and to avoid unhealthy conditions. This is so universally true that in some places such cans are not permitted to be reused without having been perfectly sterilized to prevent or destroy possible disease-germs. This precaution may be profitably employed with cans of every sort and make, and whether for mere washing or for sterilizing the can the present invention is designed to render the work easier and surer than has been possible heretofore with cans having only a small opening in their top.

In the accompanying drawings, Figure 1 is a side view, partly in sectional elevation, of a can provided with my improvements; and Fig. 2 is a vertical sectional elevation of the top of the body and the top of the can separated and a section of rubber gasket between them.

As thus shown the body B and the top or cover C are two separate and distinct parts adapted to work together with a ring-shaped rubber gasket G between them. To this end the said body has a concave channel b about its top, forming a seat for said gasket, and cover C has an outer convex seat c about its side above its edge relatively as shown, so as to leave a distinct closing portion 2 beneath said seat adapted to fit snugly within the top of the can-body and make a substantially close joint. To these ends the can-body is provided with a ring 3 about its top, having seat b therein, and cover C has a ring 4 about its bottom portion having the convex and

overhanging seating portion c and which rings, respectively, are shown herein as riveted permanently in position. Thus also the can and the cover are given permanent and rigid outlines adapted to fit each other and not liable to be bent out of shape by handling. All the foregoing features are clearly shown in Fig. 2, while the manner of seating the cover and sealing it against possible leakage is shown in Fig. 1, and said cover or top, of the can is provided with a neck 5, having a flaring or funnel-shaped mouth 6. Beneath these the said top is preferably dome shape. These parts thus constructed and equipped and having the gasket G between them are designed to be secured together during the use of the can and not to be separated until the can has been returned for cleansing. The remainder of the mechanism therefore relates to the holding of said parts together and comprises chiefly five different parts—viz., a bracket 7 on the cover and a bracket 8 on the body beneath bracket 7, a link 9 to connect said brackets, a carrier 10 for said link, and a lock 12, adapted to hold the carrier and link in engaged position on the can. I show several of these mechanisms in Fig. 1 and may use three or more, as shall be found necessary. Three give very good results and all are alike. A description of one therefore serves for all.

Both brackets are permanently secured to the cover and body, respectively, over rings 2 and 3, and link 9 is permanently looped in lower bracket 8 and pivoted in carrier 10, and loop 13 therefor in bracket 8 is purposely oblong, so as to provide for more or less play up and down for said link. This is required to adjust the parts to different thicknesses of gasket and possibly to meet other conditions. For this reason I place a set-screw 14 in bracket 8 over said loop or slot 13 to afford more or less adjustment for said link. The upper bracket has a rounded seat 14' and a lip or lug 15 at its front with a flat top and link-carrier 10, which operates measurably as a cam-lever and has a rounded end adapted to be turned into seat 14' over point or lip 15, Fig. 1, at the right, to engage it in working position, as appears at the left of Fig. 1. This turning rearward of the said carrier or lever 10 upon its seat causes an upward pull on the link because said link is pivoted to the carrier some distance above its lower end, and the link is purposely so shortened that considerable tension is exerted as the parts

come to fastening position. This also throws the pull of link 9 inward past its engagement with the lower bracket, so that there is no natural tendency for it to come loose. However, I provide a lock 12 therefor and for the bracket having the form somewhat of a button adapted to rotate on its pivot and engage its end upon the point 15. This makes the engagement of the parts perfectly secure, and the cans can be handled as ordinarily without any danger of their coming open; but the cover or top also is easily removed, and it takes only a moment to release the engaging mechanism and lift off the cover. Thus there is the freest access to the interior of the can to cleanse the same and to expose it to the sun for drying, and thus the labor of caring for cans is very materially diminished with greatly-improved conditions over the old-fashioned can.

While I have minutely described the mechanism for engaging the top temporarily with the body of the can, it is to be understood that any equivalent means for accomplishing this object may be used without departing from the spirit of the invention.

What I claim is—

1. The can-body having brackets outside at its top, and the cover having corresponding lateral projections above its seating portion, in combination with coupling-links pivoted in said brackets and carriers for said

links pivotally supported in the top thereof and adapted to be engaged over said lateral projections, and rotatable locks supported on said carriers and adapted to lock said carriers and links in engaged position. 35

2. The can-body and brackets outside at the top thereof, in combination with the can-cover, links and carriers therefor to lock said parts together, and set-screws in said brackets adapted to bear on said links and fix the working position thereof, said brackets having slots in which said links are engaged and adapted to be adjusted. 40

3. The can-body and the cover, in combination with links pivotally engaged with said body, carriers for said links on the upper ends thereof, lateral projections at the bottom of said cover over which said carriers are engaged in locking position, locks for said carriers pivoted thereon and adapted to be rotated and engage on said lateral projections and hold the links in engaged position, opposed channels in the top of the can and the bottom of the cover, respectively, and a flexible gasket therein to seal the can. 45 50 55

In testimony whereof I sign this specification in the presence of two witnesses.
